(57) **CLAIM**

The ornamental design for a shoe, as shown and described.

DESCRIPTION

FIG. 1 is a front bottom perspective view of a shoe showing my new design;

FIG. 2 is a bottom view thereof;

FIG. 3 is a rear bottom perspective view thereof;

FIG. 4 is an enlarged view showing the claimed area of FIG. 1 with environment removed for clarity;

FIG. 5 is an enlarged view showing the claimed area of FIG. 2 with environment removed for clarity; and,

FIG. 6 is an enlarged view showing the claimed area of FIG. 3 with environment removed for clarity.

The broken line immediately adjacent to and surrounding the shaded area defines the peripheral bounds of the claimed design and forms no part thereof. The broken lines depicting the remainder of the shoe show features that form no part of the claimed design.
